UNITED STATES PATENT OFFICE

HUGH W. SANFORD, OF KNOXVILLE, TENNESSEE

RAILWAY

Original application filed October 1, 1927, Serial No. 223,356, now Patent No. 1,802,445, dated April 28, 1931. Divided and this application filed March 5, 1931. Serial No. 520,420.

My improvement relates particularly to railways in which provision is made for dumping loose material through the bottom of a car at a chosen point on the track of a railway, the bottom or floor of the car consisting of doors hinged on lines transverse to the length of the car, the doors being normally in the horizontal position and adapted to turn downward on their hinges for the discharge of the material in the car.

For a similar invention, reference is made to Letters Patent of the United States, No. 1,268,390, granted to me June 4, 1918.

In the car of that patent, there are three bottom doors, one being hinged to one car axle, another being hinged to the other car axle, and the third being hinged to a rod or shaft supported at the forward end of the car.

20 The object of this invention is to provide improved means other than the axles for hinging the first and second doors. Normally the rear door is held in horizontal position by latch mechanism which to be released by means located at the discharge station or tipple, that means acting when the car reaches that station, as described in the above-mentioned Letters Patent.

The present application is a division of my former application, Serial No. 223,356, filed October 1, 1927, now patent No. 1,802,445, dated April 28, 1931, on railways, and relates particularly to the disposition of the hinge-pin or shaft on which the door or doors are hingedly supported above the lower edge of the side or end sills in order to be protected thereby from obstructions if the car should be derailed. This arrangement of the door supporting means also increases the road clearance on low-floor cars, and low-floor cars are necessary to obtain the maximum capacity for low-height cars.

In the accompanying drawings:

Fig. 1 is a side elevation of a car and track structure illustrating my improvement, the end sills or bumpers being omitted;

Fig. 2 is an elevation of the left hand or rear end of the same structure;

Fig. 3 is a longitudinal upright section 50 through the car;

Fig. 4 is a transverse upright section on the line 4—4 of Fig. 3, looking toward the left, parts being omitted;

Fig. 5 is an enlarged detail section near the line 4—4 of Fig. 3, but showing a modified form; 55

Figs. 6 to 11 inclusive, are other sectional views similar to Fig. 5, but showing the mechanism in other forms.

Referring to said drawings, A, A are track rails resting on ties A1, and piers A2. B, B are ordinary car-wheels applied to the ends of the axles C, C. D is the body of the car. D1, D1 are side sills forming portions of the car. The ends of these sills are joined by the end sills or bumpers (not shown). In the form shown, these side sills are metal channels. Boxes C1, seated in the channels of the side sills receive the axles C. (Fig. 4.)

The end of the car at the right, as viewed in the drawings, is the forward end of the car, and it is to be understood that the car moves forward for dumping and for closing the doors after the load has been discharged. The discharge is downward between the rails 70 A, and the place at which the discharge is effected is called the dumping station or tipple. Beneath the rail A, the material discharged from the car may be received by a chute or another car or any other suitable 80 device, not shown.

Three doors, E, are placed in series to form the bottom of the car. Since the rearmost of these three doors controls the series, it may be regarded as the first of the series 85 and for that reason be described first. Said door has at its forward edge three pairs of hinge members C2 and C3 (Figs. 3 and 4) as hereinafter described. At its rear edge, two bars or arms E2, are attached to the lower 90 face of the door and project a little way rearward of said rear edge.

On the rear end of the car body and in an upright plane transverse to the length of the car body are a pair of large bell cranks E3 95 (Fig. 2) pivoted at E4 to the car body. Each of said bell cranks has a hook E5, adapted to extend beneath the adjacent bar or arm E2, each bell-crank being so arranged as to bring its pivot E4, above its hook whereby the arm 100

bearing the hook may swing toward and from the upright, middle, longitudinal plane of the car when the arm E6 of the bell-crank extends horizontally outward and by its pre-
5 ponderating weight tends to tilt the bell-crank so as to move said hook toward said plane. Each of said hooks has a bevel face E7, adapted to be engaged by the adjacent bar or arm E2, when the latter is carried up-
10 ward by the upward movement of the rear portion of the door into the closed position.

When said bars E2, thus rest on the hooks E5, said door is held firmly in its upper or closed position. And this condition continues until said hooks are moved outward far enough to allow the bars E2 to descend. Said hooks are made to move outward by raising the horizontal arms E6 of the bell cranks. To cause said arms to rise automatically when the car reaches the dumping station, a cam member A3 is placed at each side of the track in position to engage the lower edge of the adjacent latch arm E6, and cause said arm to ride upward on said cam member during the further forward movement of the car, the arm E6 being extended far enough to bring said cam member into the path of said arm.

30 It is to be observed that said door will not become released unless both arms E6 are raised. Hence said door will not ordinarily become released through the accidental raising of one of said arms by means other than one of said cam members.

35 Each door has at its front edge three pairs of hinges each comprising an upper block C2, and a lower strap, C3. Rivets C4, extend through said strap and said block and the door E, and bind said members to each other.

40 The under parts of the blocks C2, are made concave to receive the upper part of a shaft F, which is parallel to and lower than the top of the adjacent axle C, and is approximately as long as the distance between the inner face of one side sill and the inner face of the other side sill.

45

In Fig. 4, each end of the shaft F rests in the lower part of an upright hanger F1, which is placed against the inner face of the adjacent side sill, far enough forward of the axle to pass the latter. Rivets, F2, extend through said hanger and through the upright web of the adjacent side sill.

This construction allows placing the hinge line of the door lower than the axle. Furthermore, the door is not supported on a member which rotates—not on the axle C, which is sometimes made rotatable in cars of this general type. Thus these hinge members C2 and C3, are not subjected to wear due to such rotation.

In Fig. 5, the structure is the same as in Fig. 4, excepting that the box C1 is omitted and the shaft F is absent, and a stub G1 is made integral with the hanger G, and the

hinge members C2 and C3 are applied to the stub, it being understood that the structure is the same at the other side of the car.

In Fig. 6, the structure is the same as in Fig. 5, excepting that the upper end of the hanger is extended in the form of a hook G2, reaching across the upper flange of the side sill and secured to said flange by a rivet F2. 70

In Fig 7, the hanger H is not attached to the side sill in any manner. On the side sill rests a wood sill H1, on which is a part of a wooden side wall H2. The hanger H extends over the inner face of the side sill and over the inner faces of the wood sill and a part of the wooden side wall. Bolts H3, join this hanger to the wood sill and to the side wall. The lower part of the hanger supports the shaft F, which supports the hinge members C2 and C3. 75 80

In Fig. 8, the parts are the same as in Fig. 7, excepting that the shaft F is absent and a horizontal stud H4 is made integral with the hanger H, and supports the hinge members C2 and C3. 85

In Fig. 9, the hanger I is not connected with the side sill in any manner. A wooden side wall I1 rests on the upper flange of the side sill. The hanger extends from the inner face of the side sill and the inner face of said wall. A strap I2, extends over the outer face of the side sill and is secured thereto by rivets I3, and extends outward under the upper flange of the side sill and upward over the outer face of said wall. Rivets or bolts I4, extend through said strap and said wall and through the upper part of the hanger I, for binding said strap and said wall and said hanger to each other. A horizontal stud I5, is integral with the lower end of the hanger I, and supports the hinge members C2 and C3. 105

In Fig. 10, an inclined metal plate wall J1, has its lower edge flanged horizontally and seated on the upper flange of the side sill and secured to said flange by means of a rivet J2. The hanger J, extends over the inner face of the side sill and over a part of the inner face of the side wall J1. A strap J3, extends over the outer face of the side sill and outward under the upper flange of said sill and thence upward to meet the outer face of the side wall. A rivet J5, extends through the upper part of said strap and through said wall and through the upper part of the hanger to bind said three members to each other. Rivets J4 join the strap and sill together. The lower end of the hanger J, supports a shaft J6, which receives the hinge members C2 and C3.

In Fig. 11, an inclined plate metal wall ¹²⁵ L1, has its lower edge flanged outward horizontally and seated on the upper flange of the side sill and secured thereto by rivets L2. The hanger L, extends over the inner face of the side sill and is free therefrom and extends upward over the inner face of the side ¹³⁰

wall and is secured to said wall by means of rivets L3. The hanger extends upward over said wall indefinitely and performs the function of a strap as well as serving as a hanger

5 for supporting the shaft L4.

It has already been stated herein that the doors are not hinged to rotary axles which would subject the hangers and the axles to wear and consequent weakening.

10 It is also to be noted that the hangers rest closely against the car body side structures and are of sufficient length to make contact with said side structures over a large area which facilitates firm attachments to the side

15 structures. That facilitates fixing the hangers to the side structures by means of rivets or bolts.

Thus placing the hangers closely against the faces of the body side structures facilitates bending the upper ends of the hangers outward over adjacent parts of the side structures, as shown in Figs. 6, 7, 8, 10 and 11. Outward bending of the hangers in contact with the side structures aids in giving to the 25 hangers a strong engagement with the side structures.

In Fig. 6, the upper end of the hanger hooks over the upper face of the side sill D1. Furthermore, in all the forms, the hanger is given lateral support against the inner face of the side sills. Giving these hangers this extended contact and support allows making the hangers of relatively thin metal, whereby the hangers occupy small space in horizontal 35 cross-section and thus avoid objectionable reduction of capacity in the lower part of the car body.

By the hinge structures shown, provision is made for placing the doors E on a hinge 40 line or axis above the lower face or flange of the side sill D1. In Figs. 5, 6, 8 and 9, horizontal studs support the door, each of the entire studs being above the level of the lower face of the side sill D1. Figs. 4, 7, 10 and 11 indicate a rod, in lieu of studs, to bring the axial line of the door above the lower face of the side sill. In Figs. 10 and 11, the lower part of the hinge member C3, is above the lower face of the side sill D1.

50 For practical operation, it is important to bring the forward part of the door and the door-supporting members high relative to the lower flanges of the side sills, in order that when a car becomes derailed or runs over a rock between the track rails, the door-supporting members and the forward part of the door will be less likely to strike the rock or other obstruction.

Although the doors of the car are curved 60 downward, below the hinge line of the doors, they may meet such obstructions without serious damage, for the obstruction may lift the main part of the door.

65 This arrangement or location of the door supporting means also increases the road

clearance on low-floor cars, and low-floor cars are necessary to obtain the maximum capacity for low height cars.

I claim:

1. In a dumping car, the combination of a 70 protecting frame structure, wheels and axles for supporting said structure, a plurality of transversely hinged drop-bottom dumping doors for said car, hangers carried by the frame structure and means carried by the hangers for hingedly supporting at least one of said doors, said means having the hinging axis disposed above the bottom of the protecting frame structure.

2. In a dumping car, the combination of a 80 protecting frame structure, wheels and axles for supporting said structure, a plurality of transversely hinged drop-bottom dumping doors for said car, hangers carried by the frame structure and means carried by the hangers for hingedly supporting at least one of said doors for swinging movement about an approximately horizontal axis, said axis being disposed above the bottom of the protecting frame structure.

3. In a dumping car, the combination of a 90 protecting frame structure, wheels and axles for supporting said structure, a plurality of transversely hinged drop-bottom dumping doors disposed within the confines of the frame structure, hangers carried by the frame structure and means carried by the hangers for hingedly supporting said doors for swinging movement about approximately horizontal axes, said axes being permanently disposed above the bottom of the protecting frame structure.

4. In a dumping car, the combination of a 100 protecting frame structure, wheels and axles for supporting said structure, a plurality of transversely hinged drop-bottom dumping doors disposed within the confines of the frame structure, one or more hangers and a hinge-pin carried thereby for hingedly supporting at least one of the doors, said hinge pin being permanently disposed between the horizontal planes of the top of the axle and the bottom of the frame structure.

5. In a dumping car, the combination of a 110 protecting frame structure, wheels and axles for supporting said structure, a plurality of transversely hinged drop-bottom dumping doors for the car, one or more hangers, and a hinge-pin or bar other than the axle carried by said hangers for hingedly supporting each of the doors for swinging movement about an approximately horizontal axis, said hinge-pin being entirely and permanently disposed between the horizontal planes of the top of the axle and the bottom of the frame structure to be protected by said frame structure.

6. The combination of car body side structures in which are sills, axles supporting the sills, wheels carrying said axles, fixed hanger members extending transversely over the 120

125

130

side structures adjacent and below the level of the axles, and making extended lateral contact with the side structures and secured thereto, horizontal door supporting means carried by the hanger members and disposed within the confines of the planes of the top of the axle and the bottom of the sills to be protected thereby, and one or more releasable drop bottom doors hinged to said door supporting means.

7. The combination of car body side structures in which are sills, axles supporting the side sills, wheels carrying said axles, fixed hanger members extending transversely over the side structures adjacent and below the level of the axles, and making extended lateral contact with the side structures and secured thereto, horizontal door supporting means carried by the hanger members and permanently disposed within the confines of the planes of the top of the axles and the bottom of the sills to be protected thereby, a bottom door having its forward portion hinged to the door supporting means, and releasable means for supporting the rear edge of said door when the latter is in the closed position.

8. The combination of car body side structures in which are sills, axles supporting the side sills, wheels carrying said axles, fixed hanger members extending transversely over the side structures adjacent and below the level of the axles, and making extended lateral contact with the side structures and secured thereto, horizontal door supporting means carried by the hanger members and permanently disposed within the confines of the planes of the top of the axles and the bottom of the sills to be protected thereby, a bottom door having its forward portion hinged to the door supporting means, releasable means for supporting the rear edge of said door when the latter is in the closed position, a second bottom door having its forward portion hinged to the next forward door supporting means and having its rear edge normally supported by the forward edge of the first-mentioned door in position for release from said door when the latter is turned downward into the discharge position.

9. In a dumping car, the combination of a protecting frame structure, wheels and axles for supporting said structure, a plurality of transversely hinged drop bottom dumping doors for said car, hanger members carried by the frame structure and means carried by the hanger members and disposed below the axle and above the bottom of the protecting frame structure for hingedly supporting the doors.

10. In a dumping car, the combination of a protecting frame structure, wheels and axles for supporting said structure, a plurality of transversely hinged drop-bottom

dumping doors for said car, hanger members carried by the frame structure and means carried by the hanger members for hingedly supporting one or more of the doors about an approximately horizontal axis, said axis being disposed below the axis of the axle and above the bottom of the protecting frame structure.

11. In a dumping car, the combination of a frame structure having sills, wheels and axles for supporting said structure, a plurality of transversely hinged drop-bottom dumping doors for said car, hangers carried by the sills and means carried by the hangers for hingedly supporting one or more of the doors for swinging movement about an approximately horizontal axis, said axis being disposed below the axis of the axle and above the bottom of the sills.

12. In a dumping car, the combination of a frame structure having side sills, wheels and axles for supporting said structure, a plurality of transversely hinged drop-bottom dumping doors for said car, one or more hangers carried by the side sills, and a hinge-pin or bar carried by the hanger on which an edge of each of one or more of said doors is hingedly supported, said pin or bar being supported entirely below the axle and above the bottom of the side sills in protected position, and releasable means for supporting the opposite edge of at least one of said doors.

13. In a dumping car, the combination of a protecting frame structure, wheels and axles for supporting said structure, a plurality of transversely hinged drop-bottom dumping doors for said car, hangers carried by the frame structure, means other than the axles and carried by the hangers for hingedly supporting each of a plurality of said doors, said means having the hinging axes disposed above the bottom of the protecting frame structure, releasable means for supporting an edge of one of said doors in closed position and to permit said door to drop and rotate, and a second door adjacent to said last-mentioned door and having an edge supported in position to be released by the dropping and rotation thereof.

14. In a dumping car, the combination of a protecting frame structure, wheels and axles for supporting said structure, a plurality of transversely hinged drop-bottom dumping doors disposed within the confines of the frame structure, hangers carried by the frame structure, means other than the axle and carried by the hangers for hingedly supporting each of a plurality of said doors for swinging movement about approximately horizontal axes, said axes being permanently disposed above the bottom of the protecting frame structure, releasable means for supporting an edge of one of said doors in closed position and to permit said door to

drop and rotate, and a secnd door adjacent to said last-mentioned door and having an edge thereof supported in position to be released by the dropping and rotation of said door.

- 6 15. In a dumping car, the combination of a protecting frame structure, wheels and axles for supporting said structure, a plurality of transversely hinged drop-bottom dumping doors disposed within the confines of the frame structure, one or more hangers carried by the frame structure, a hinge pin carried by the hanger for hingedly supporting each of a plurality of the doors, said 10 hinge pin being permanently disposed between the horizontal planes of the top of the axle and the bottom of the frame structure, releasable means for supporting an edge of one of said doors in closed position to permit 15 said door to drop and rotate, and a second door adjacent to said last-mentioned door and having an edge supported in position to be released by the dropping and actual rotation of said door.
- 20 16. In a dumping car, the combination of a protecting frame structure, wheels and axles for supporting said structure, a plurality of transversely hinged drop-bottom dumping doors for said car, hangers carried 25 by the frame structure, means carried by the hangers and disposed below the axle and above the bottom of the protecting frame structure for hingedly supporting the doors, releasable means for supporting an edge of 30 one of said doors in closed position to permit said door to drop in rotary motion, and a second door adjacent to said last-mentioned door and having an edge supported in position to be released by the dropping and actual rotation of 35 said door.
- 35 17. In a dumping car, the combination of a frame structure having side sills, wheels and axles for supporting said structure, a plurality of transversely hinged drop-bottom dumping doors for said car, one or more hangers carried by the side sills, a hinge-pin or bar carried by the hanger and on which an edge of each of one or more of said doors is hingedly supported, said pin or bar being 40 supported entirely below the axle and above the bottom of the side sills in protected position, releasable means for supporting the opposite edge of at least one of said doors, a second door adjacent to said last-mentioned 45 door and having an edge supported in position to be released by the dropping of said door.
- 50 55

In testimony whereof I have signed my name, this 25th day of February, in the year one thousand nine hundred and thirty-one.

HUGH W. SANFORD.
